UNITED STATES PATENT OFFICE

105,076

DESIGN FOR A DRESS

Albert Ruchman, New York, N. Y.

Application May 5, 1937, Serial No. 69,169

Term of patent 3½ years

To all whom it may concern:

Be it known that I, Albert Ruchman, a citizen of the United States of America, residing in Manhattan, county of New York, and State of New York, have invented a new, original, and ornamental Design for a Dress, of which the following is a specification, reference being had to the accompanying drawing, forming part thereof, wherein,

The characteristic feature of my design resides in the combination on the double collared dress as shown of the horizontal bands of embroidered trim, said bands being grouped and spaced as shown.

I claim:

The ornamental design for a dress, substantially as shown and described.

ALBERT RUCHMAN.
